HENRY A. AMMANN, OF SPOKANE, WASHINGTON, ASSIGNOR TO DIAMOND INDIVIDUAL TOWEL SYSTEM CO., OF SPOKANE, WASHINGTON, A CORPORATION OF WASHINGTON.

INDIVIDUAL-TOWEL CABINET.

1,302,753.

Specification of Letters Patent.

Patented May 6, 1919.

Application filed April 29, 1918. Serial No. 231,380.

To all whom it may concern:

Be it known that I, HENRY A. AMMANN, a citizen of the United States, residing at Spokane, in the county of Spokane and 5 State of Washington, have invented new and useful Improvements in Individual-Towel Cabinets, of which the following is a specification.

This invention relates to improvements in 10 individual towel dispensing cabinets.

The invention has to do more particularly with an individual towel dispensing cabinet wherein the clean towels are disposed in stack form, on edge, upon a shelf. The 15 towels are engaged on one side of the stack, by an actuated follower, and on the other side of the stack the towels are engaged by the back of the cabinet in order to maintain the towels on edge in stack form. That portion 20 of cabinets of this character in which the clean towels are disposed, is limited in space to accommodate the maximum number of clean towels for which the cabinet is designed. Therefore when the cabinet is 25 charged with clean towels, there is very little additional room. Thus in many prior devices, this type of follower board has been actuated by weights, cords attached to the follower extending downwardly through the 30 shelf and on which the weights are pendently hung.

It has been found in practice, especially in short length cabinets adapted to be disposed above wash stands, that the height or length 35 of the cabinet can be very greatly reduced by substituting a spring, for actuating the follower, instead of weights. Furthermore, when weights are utilized, they must extend down into the soiled towel compartment and 40 therefore it is necessary to house the weights to avoid interference with the soiled towels.

Now therefore one of the objects of this invention is to provide a simple and efficient means for actuating the follower so as always 45 to maintain the latter in snug contact against the towels as the stack is gradually decreased. In order to eliminate two springs, and also obtain an efficient equalizing action, a single spring device has been 50 devised, which is the object of this invention, one end of the spring being operatively connected with one end of the follower and the remaining end of the spring being operatively connected with the remaining end of

the follower. The spring is freely movable 55 and the lines or flexible cords, or other operative means whereby the spring is connected with the follower, are likewise slidably connected with the spring. Therefore, should the cords be of unequal length or if 60 one cord should stretch more than the other, this floating spring compensates for such irregularities and exercises a uniform pull upon each end of the follower.

Specifically speaking, it is a feature of this 65 invention to provide each end of the spring with a pulley, around each pulley is trained the bight of a cord or flexible line, the ends of which are connected at superposed points with the back of the follower, near each end 70 of the latter. Thus the pull of the spring, or the thrust exercised by the spring, is not only imparted to both ends of the follower, but also at different vertical points along the follower, thereby tending to keep the follower 75 in flat abutting relation against the towel stack.

It is a further feature of this invention to mount the spring outside of the compartment containing the clean stack of towels 80 whereby a relatively large sized and highly resilient spring may be utilized, the same having ample room for lengthening or shortening under its own resiliency as the follower takes different positions as a result of 85 spring pull, or otherwise.

The invention has other objects and features which will be more fully described in connection with the accompanying drawing, and which will be more particularly pointed 90 out in and by the appended claims.

in the drawing:

Figure 1, is a view in front elevation of a form of cabinet of relatively contracted length, and suitable for office use, a portion 95 of the same being broken away to better illustrate internal parts.

Fig. 2, is a sectional view on line 2—2 of Fig. 1.

Fig. 3, is a sectional view on line 3—3 of 100 Fig. 1.

Like characters of reference designate similar parts throughout the different figures of the drawing.

As illustrated, the cabinet comprises a 105 back 1, which extends the full length thereof, and side walls 2 which likewise extend the full length of the cabinet. A bottom

wall 3, together with a front wall 4, form with the sides and back a soiled towel receptacle 5. A shelf 6 extends forwardly from the back 1 and is designed to support a stack of towels 7, in an upright, and on edge position. One side of the stack of towels is maintained vertical by the back 1, and the other side of the stack of towels is maintained vertical by a follower 8. Thus the 10 clean towels are disposed in a compartment, comprising the side walls 2, the back 1, and the follower 8, the towels fairly snugly fitting said compartment. The cabinet is proportioned so that a slight cleared space 9 will be provided between the end of the 15 towel stack and the side walls 2. The depth of the shelf 6 is proportioned in accordance with the capacity for which the cabinet is designed, either 50 or 100 towels being the 20 usual initial charge, the cabinet being designed accordingly.

Strictly speaking, the rear side of the towel stack does not directly engage the back 1, there being provided projecting edges 10 and 11 for engagement with the towels for the purpose of holding the towels in broadly spaced relation with respect to the back 1. The projecting edges 10 and 11 are straight edges, and the same may be 30 formed by bending the margins of a strip 12, into the position shown. The strip 12 is rigidly secured to the back, and therefore it may form a part of the back structure, pat- entably speaking.

35 Now it will be clear that when a cabinet is charged with clean towels, substantially all of the space in the clean towel compartment will be occupied by the clean towels themselves. In the absence of enlargement 40 or extension of some character, no room will be present for actuating for the follower. If the cabinet is enlarged to provide for such actuating in the clean towel compartment, then the cabinet becomes bulky 45 and lacking in compactness.

Therefore it is a feature of this invention to dispose the follower actuating means outside of the clean towel compartment, which will now be designated as a whole by refer- 50 ence numeral 13.

Next referring to the improved follower actuating means, the same is specifically shown in the form of a spring 14 which is shown disposed in subjacent relation to the 55 shelf 6. Spring 14 is of the coiled contractile type and its diameter will preferably be such that its length need not be excessive in order to afford the necessary degree of resiliency. Furthermore, because of the length of the 60 spring due to its somewhat enlarged diameter, the wire forming the convolution may be relatively small in cross section, hence this character of spring even when extended to its limit, will not exert an excessive pres- 65 sure on the follower, it being the intention

to lightly engage the follower against the towels to avoid generating too much friction when the towels are pulled out one by one. The spring 14 is disposed beneath shelf 6 and the latter is provided with suitable 70 opening 15 through which cords or flexible lines may extend to connect the spring with the follower, as will be presently described. It is desirable to inclose the spring and therefore I provide an inclosing shelf 16, 75 extending beneath the spring, and a covering front 17 extending upwardly into abutting relation with the bottom of the shelf 6. The covering front 17 fits snugly between the walls 2 and therefore by reason of its ad- 80 ditional engagement with the shelf 6, only one screw 18 is required to secure the front 17 in position. The front 17 is preferably extended downwardly a slight distance, and a shelf 19 may be secured to the bottom 85 thereof. This shelf 19 affords a convenient support for a comb, brush and like toilet articles. There will be no occasion for the user to gain access to the spring and therefore when the cabinet is assembled, the cov- 90 ering front will remain in position continu- 95 ously, unless it was necessary to repair the spring or renew connection with one of the lines.

The spring at each end is provided with 95 a bent terminal 20 on which a block 21, each with a pulley 22, is mounted. A cord or flexible line 23 has its bight trained through or about pulley 22, and this cord or line is trained about pulleys 24 and 25, 100 mounted upon side walls 2. The cord 23 extends upwardly through the opening 15, and one cord end 26, is trained through pul- 105 ley 27, mounted upon the back 1, and ex- tends therefrom forwardly toward the fol- lower 8 to which it is secured at 28. The remaining end 29 of said cord is trained about pulley 30, on the back 1, and extends forwardly toward the follower to which it is secured at 31. By providing superposed 110 connections of the cord with the follower, and at each end thereof, it is possible to urge the follower into a towel engaging position with the entire area of the follower in flat abutting relation against the back. If the 115 stack is slightly out of true, the follower will seek to take a similar position, it being understood that the towels themselves do not move, as the stack is being exhausted, the follower itself being the only movable part. Thus by reason of these connections at each 120 end of the follower, at points closely adja- cent to the retaining edges 10 and 11, it will be seen that the follower will function to hold the towel stack in substantially uni- 125 form engagement with these retaining edges. It will be seen that these retaining edges project forwardly a sufficient distance so that when the follower is holding the last towel against said edges, the edges will prevent 130

the follower from engaging the pulleys 27 or 30 and thereby free the last one or two towels by not permitting the follower to engage the retaining edges.

5 Now it will be seen and understood that the flexible line connection with the right hand portion of the follower, is identical with that shown in full lines at the left hand side of Fig. 1, the spring being free to move 10 endwise in the spring chamber without any restraint whatsoever. Thus if the towels were stacked in such a manner that one side was thicker than the other, the spring would pull uniformly on both ends of the follower 15 because the spring 14 is free to bodily move longitudinally in the spring chamber. Furthermore, if the cords or flexible lines 23 should not be cut at exactly the same length, or in case one cord stretched with respect to 20 the other, the spring would likewise equalize and compensate for any such irregularity by taking a position dependent upon the correction of such irregularity and causing the follower to function in an absolutely 25 normal manner. If the cords were fastened to the ends of the spring, then each cord would have to be of the same length, identically, and if one cord stretched, then the spring would pull to a greater extent on the 30 unstretched cord and would impose a thrust on the follower 8 which would tend to shift the follower out of a normal position. However, by having the bight of the flexible lines trained through the pulleys, the lines 35 can shift so that each line, throughout its length, will always be taut. Furthermore, in the case of an irregular stack of towels, the lines themselves would equalize because of their pulley connection with the spring, 40 and therefore if the towels resist movement of the follower in a manner to cause the follower to tilt from a normal vertical position, the lines will shift in their pulley connections so that they will always be taut irrespective of such abnormal position of the 45 follower. Therefore, it will be seen that the lines equalize as well as the spring.

In putting the towels into the towel compartment 13, the spring permits of the greatest 50 flexibility of movement of the follower, either end for end, or bodily, when the follower is pulled out by hand in order to insert the towels into position.

The proportions are such that the end 55 pulleys 22, of the spring 14, would engage the pulleys 24 and 25, thereby limiting outward movement of the follower to such a point as would strain the spring.

The towels are strung upon a flexible 60 stringer 32, which may be removably secured to the back 1, at 33, in any desirable manner, at one end thereof, and which is fastened at 34 to the bottom of the soiled towel receptacle in a suitable removable manner. Inasmuch as this flexible stringer has been

hereinbefore claimed and described in prior patents, no further detailed description thereof is necessary.

The great advantage of the construction herewith shown, is that it is absolutely 70 noiseless in its operation. Repairs and renewals can readily be made. Because of the disposition of the spring with its axis parallel with the shelf, a relatively great length of coil can be utilized, and therefore 75 the coil can be proportionately designed so as to exert a pull on the follower with the least possible variation of power thereby nearly approximating uniform tension of the follower against the towels.

80

It is believed that the advantages and utility of this invention will be clearly understood from the foregoing description, and while I have herein shown and described one specific form of my invention, I 85 do not wish to be limited thereto except for such limitations as the claims may import.

I claim:—

1. In an individual towel cabinet, a compartment for the clean towels including a 90 follower, and a floating spring having its ends operatively connected with said follower to actuate the same.

2. In an individual towel cabinet, a shelf for supporting a stack of towels on edge, 95 a back and a follower engaging opposite sides of the stack to maintain the towels in stack form, a contractile coil spring below said shelf freely movable to lengthen or shorten or move bodily, flexible lines connected with one end of said spring and extending up through said shelf and connected with one end of said follower, and flexible lines connected with the remaining end of said spring and extending up through said 100 shelf and connected with the remaining end of said follower whereby said spring will actuate said follower against the stack as the latter is being exhausted.

3. In an individual towel cabinet, a shelf for supporting a stack of towels on edge, 110 a back and a follower engaging opposite sides of the stack to maintain the towels in stack form, a freely movable contractile coil spring below said shelf having a pulley on each end thereof, a flexible line having its bight trained through one of said pulleys and its two ends secured to one end of said follower, a flexible line having its bight trained through the remaining pulley and having its ends secured to the remaining end of said follower, and sets of pulleys 115 guiding said flexible lines to exert the thrust of the spring on said follower to move the latter against the stack as the latter is being exhausted.

4. In an individual towel cabinet, a shelf for supporting a stack of towels on edge, 120 a back and a follower engaging opposite sides of the stack to maintain the towels in 125

- stack form, a single freely movable spring below said shelf, and flexible lines movably connected with said spring and secured to said follower for moving the latter against 5 said stack as the latter is being exhausted.
5. In an individual towel cabinet, a compartment for the clean towels including a follower for holding the towels on edge, freely movable compensating spring means 10 outside of said compartment for actuating said follower, and devices having compensating connection with said spring means for equalizing the application of thrust thereof on said follower irrespective of the 15 posture assumed by said stack.
6. In an individual towel cabinet, a compartment for supporting a stack of towels on edge including a shelf and a follower, a spring disposed below and in parallel relation 20 with said shelf, and means attached to the ends of said spring for transmitting thrust thereof to said follower.
7. In an individual towel cabinet, a compartment for the clean towels including a shelf and a follower, a follower actuating spring below and in parallel relation with 25 said shelf, an inclosing shelf below said
- spring, an inclosing front secured against the front edge of said inclosing shelf and being in edge abutting relation against the 30 bottom of the towel supporting shelf whereby a single fastening device will hold said front in position and form a compartment for said spring.
8. In an individual towel cabinet, a compartment for the clean towels including a supporting shelf and a follower, a spring below and in parallel relation with said shelf and connected with said follower, an inclosing shelf below said spring, an inclosing front having its back abutting against 35 said inclosing shelf and its upper edge abutting against said towel supporting shelf for inclosing said spring, and a toilet article 40 shelf mounted on said front.
9. In an individual towel cabinet, a compartment for the clean towels including a follower, a spring for actuating said follower, and a flexible line having its bight 45 slidably connected with said spring and having its ends connected with said follower.
- In testimony that I claim the foregoing as my own, I hereby affix my signature.

HENRY A. AMMANN.
